UNITED STATES PATENT OFFICE.

DONALD MITCHELL WESTON, OF DALTON, MASSACHUSETTS, ASSIGNOR TO BYRON WESTON COMPANY, OF DALTON, MASSACHUSETTS, A CORPORATION OF MASSACHUSETTS.

DESIGN FOR A CALENDAR MOUNTING.

61,265.

Specification for Design.

Patented July 18, 1922.

Application filed April 7, 1922. Serial No. 1,630. Term of patent 14 years.

To all whom it may concern:

Be it known that I, DONALD MITCHELL WESTON, a citizen of the United States, residing at Dalton, in the county of Berkshire, State of Massachusetts, have invented certain new, original and ornamental Design for a Calendar Mounting, of which the following is a description, reference being had to the accompanying drawing forming a part thereof.

The figure is a front view of a calendar mounting, showing my new design.

I claim:

The ornamental design for a calendar mounting, as shown.

In testimony whereof, I affix my signature.

DONALD MITCHELL WESTON.
